UNITED STATES PATENT OFFICE.

GUSTAF E. WALLIN, OF CHICAGO, ILLINOIS.

LINOTYPE-SLUG HOLDER.

SPECIFICATION forming part of Letters Patent No. 699,728, dated May 13, 1902.

Application filed November 30, 1901. Serial No. 84,267. (No model.)

To all whom it may concern:

Be it known that I, GUSTAF E. WALLIN, a citizen of the United States, residing at Chicago, in the county of Cook and State of Illinois, have invented new and useful Improvements in Linotype-Slug Holders, of which the following is a specification:

This invention relates to a linotype-slug holder adapted for use in holding slugs—type-lines produced by type-machines or any machine that sets type in solid lines or lines of one piece—in position on galleys. By the present methods printers and printing houses handling "linotype" matter, so called, are experiencing great trouble from the loss of the lines at the bottom of well-filled galleys; and the object of the improved device is to apply sufficient holding power along the upright surface of the last slug to prevent the type-lines from becoming loosened, thus insuring a perfectly secure slug, and thereby also not only are the end lines prevented from falling from the galley, but the matter is kept "on its feet," and a perfectly level surface is presented to the proof-press, giving improved results in taking proofs.

The invention consists in the construction and arrangement of the several parts, which will be more fully hereinafter described and claimed.

In the drawings, Figure 1 is a plan view of what is known as an "all-zinc" galley broken through and showing a series of slugs applied thereto and held against movement by the improved holder adapted for this particular class of galley. Fig. 2 is a transverse vertical section on the line 22 of Fig. 1. Fig. 3 is a detail perspective view of the holder. Fig. 4 is a detail perspective view of a modified form of the holder for use on what are known as "all-brass" galleys which have slightly curved outer sides.

Similar numerals of reference are employed to indicate corresponding parts in the several views.

Referring to the form of the device shown by Figs. 1, 2, and 3, the numeral 1 designates a substantially rectangular pressure-frame of considerable length and adapted to be placed directly against the side of the last slug of a series of the latter which are disposed in the galley. The frame 1 is of such dimensions

relatively to the slugs that the pressure will be extended over the greater portion of the side of the slug with which the frame engages. 55 The end 2 of the frame, which bears against the inner surface of the side flange of the galley is of less vertical height than the opposite end and forms a gripping or biting jaw. From the lower corner 3 of the end 4 a member 5 extends diagonally outwardly from the lower portion of the frame 1 and is formed into a jaw 6 of equal vertical extent to and parallel with the jaw 2, the pressure-face of the jaw being formed with a vertical slot 7 to provide 65 biting edges to engage the inner surface of the flange of the galley and prevent the said jaw from slipping or moving from its adjusted position; and thereby reliably hold the frame 1 with a positive pressure against the last slug 70 of a series of slugs. From the jaw 2 the material of which the holder is formed is continued inwardly and bent to produce an eye 8, and from said eye the material is continued outwardly and bent downwardly to form a clamping-loop 9, having its side opposite that continued from the eye 8 similarly formed and merging into an upper second eye 10, which is continuous with the jaw 6. The upper member of the frame 1 is bent at right angles and passed 80 through the eyes 8 and 10 and terminally secured to the eye 10, and by this means the jaws 2 and 6 are prevented from laterally spreading or pulling apart. The material of which the improved holder is formed is preferably stiff steel wire and is of one continuous piece. It has been found that cast-steel wire properly tempered serves the purpose better than any other material. The clamping-loop 85 9 stands outwardly from the jaws 2 and 6 a 90 distance less than the flange or part of the galley which enters between the said loop and jaws, so that a resilient binding action will be set up on the engaged part of the galley to prevent displacement of the holder, and particularly in view of the two separated points of contact obtained through the said jaws 2 and 6, which will prevent the holder from having a rocking movement and assist in maintaining it in immovable position. The 100 jaw 6, as clearly shown by Fig. 1, is at a distance from the last slug of the series of slugs held in the galley by the improved device, and in view of the formation of the slot 7 said

jaw 6 will be held against slipping and brace the jaw 2. In applying the device illustrated by Figs. 1, 2, and 3 the clamping-loop 9 is slipped over the one side flange of the galley, and the entire holder is then pushed up closely against the last slug of the series of slugs in the galley to bring the pressure-frame 1 tightly against said last slug.

The modified form of the device shown by Fig. 4 is in all particulars precisely similar in construction to the device shown by Fig. 3, and similar reference-numerals are employed in connection therewith, with the exception of the clamping-loop 11, which is convex to fit over the side of what is known as an "all-brass" galley and has a corresponding convex curvature. In this modification is also shown a reinforcing addition in the form of straps 12, connecting the lower member of the frame 1 and the member 5 close to the bases of the jaws 2 and 6 to serve as further means for preventing said jaws from spreading. This strap will also be used at times in connection with the form of the device shown by Fig. 3.

The improved device is simple and effective in its construction and operation, strong and durable in its wearing qualities, and will prove to be a valuable acquisition to the art to which it pertains. It is obvious that changes in the form, dimensions, proportions, and minor details may be resorted to without in the least departing from the principle of the invention.

Having thus fully described the invention, what is claimed as new is—

1. As an improved article of manufacture, a linotype-slug holder comprising a pressure

member to engage a slug, a pair of spaced resilient jaws, and a single clamping-loop extending outwardly from and common to both of the said jaws, a space being formed between the clamping-loop and the jaws to adapt the latter to be frictionally and slidably as well as freely removable in relation to the side portion of a galley.

2. As an improved article of manufacture, a linotype-slug holder comprising a pressure-frame having a pair of spaced jaws at one end, and a clamping-loop coacting with the said jaws and spaced outwardly from the latter, the jaws and clamping-loop being adapted to removably and adjustably engage the side of a galley and the jaws to contact with the latter at separated points on the same surface.

3. As an improved article of manufacture, a linotype-slug holder comprising a pressure-frame to bear against a slug, and a pair of spaced jaws and a clamping-loop, and said jaws being adapted to frictionally and slidably engage the inner and outer faces of one side of a galley.

4. As an improved article of manufacture, a linotype-slug holder comprising a pressure-frame to bear against a slug, and a pair of spaced jaws and a clamping-loop, said jaws being adapted to bear against the inner and outer faces of one side of a galley, one of the jaws being slotted to provide biting edges.

In testimony whereof I affix my signature in presence of two witnesses.

GUS. E. WALLIN.
